UNITED STATES PATENT OFFICE.

CHARLES J. KIRK, OF NEW CASTLE, PENNSYLVANIA.

HEAT-TREATING FURNACE.

1,337,454.

Specification of Letters Patent. Patented Apr. 20, 1920.

Application filed June 5, 1919. Serial No. 301,975.

To all whom it may concern:

Be it known that I, CHARLES J. KIRK, a citizen of the United States, and resident of New Castle, in the county of Lawrence 5 and State of Pennsylvania, have invented a new and useful Improvement in Heat-Treating Furnaces; and I do hereby declare the following to be a full, clear, and exact description thereof.

10 My invention relates to a heat treating furnace. In an application filed by me on the 1st of March, 1919, Serial No. 280,131, I have illustrated and described a heat treating 15 furnace in which the objects to be heated are not subjected directly to the hot products of combustion, but are subject to the indirect action of the heat and suitable for the burning of pottery or the annealing of 20 metal. In that application, the furnace was divided into two compartments with tracks in each compartment, the cars on one track entering in the opposite direction from the cars on the other track, provision being 25 made for utilizing the heat emanating from the heated cars, and the objects carried thereby on one track for aiding and heating the objects on the cars entering the furnace from the opposite end on the other track, 30 by providing the partition wall with a series of openings at the top and bottom to allow for the free circulation, so that the hot air passing through the upper openings will pass down through the other compartment, and through the lower openings back 35 into the original compartment whereby a constant circulation is maintained and the time required for treatment greatly reduced as well as the amount of fuel required. 40 The present invention has relation to a furnace of this character and the special improvement will be more particularly herein-after set forth and claimed.

In the accompanying drawing, Figure 1 45 is a plan view partly in section broken away of my improved furnace; Fig. 2 is a longitudinal section broken away; Fig. 3 is an enlarged cross section on the line 3—3, Fig. 1; and Fig. 4 is a longitudinal vertical section of a portion of one of the compartments of the furnace showing the face of the inner wall thereof.

In the drawing, the numeral 2 designates 50 a suitable base or foundation upon which the furnace is erected, said furnace consist-

ing of the side walls 3 and the top or crown 4. The heating furnace 5 is divided into two compartments by the partition wall 6 which also aids to strengthen and support the roof 4. This partition wall is provided 60 with the opening 7 arranged at intervals at the top and adjacent to the bottom thereof, and preferably staggered with relation to each other.

Suitable combustion chambers 8 and 9 are 65 provided at each side of the furnace for supplying the heat whether gaseous or solid fuel is employed. These furnaces may be of any suitable construction, and I have only illustrated them in a diagrammatic 70 form in Fig. 1.

Communicating with the combustion chambers 8 and 9 are the flues 10 and 11, respectively, in the side walls of the furnace. The flues 10 communicate with each 75 other through the flue 12 which passes over the top of the furnace chamber 5 and the flues 11 communicate through a like flue 13.

These flues 10 and 11 are non-communicating, being separated from each other by 80 the wall 14. Outlet flues 15 and 16 are provided for the flues 10 and 11, respectively.

The inner walls of the flues 10 and 11 are made up of hollow tiles 17, said tiles being supported on the ledge 18 and being set 85 close together to form tight joints with each other. The upper and lower ends of these tiles are open communicating with the two compartments of the heating chamber and the upper and lower ends of said tiles are 90 preferably beveled as indicated at 19. These tiles form an insulating wall between the flues 10 and 11 and the heating chamber, so that the heat from said flues is not directly conveyed through the wall to the objects to 95 be treated but the hollow tiles furnish an opportunity for the circulation of the air so as to protect said base against the direct radiation, and furthermore, the wall itself is protected and its life prolonged.

100 Within the heating chamber are the tracks 20 and 21 upon which the cars 22 and 23 travel, respectively, said cars being made up of suitable refractory material to withstand the high heat to which they are subjected 105 in passing through the furnace. The objects 24 to be heated are arranged upon said cars, so as to allow the heat to circulate in and around the same during their passage through the furnace.

110

The ends of the furnace are provided with suitable doors 25.

In the operation of the furnace, the ware mounted on the cars 22 is introduced into the furnace at one end, and the ware mounted on the cars 23 is introduced on the opposite track at the other end of the furnace. Heat from the combustion chambers 8 and 9 passes through the flues 10 and 11, and also by the flues 12 and 13 to the flues at the opposite side. Cars of the ware as they pass through the heating chamber are heated to a high temperature getting hotter as they near the discharge end. Accordingly the heat given off by said highly heated cars and the objects carried thereon ascending will pass through the openings 7 in the partition 6, and said heat is employed for assisting in the heating of the cold cars which are coming in on the next track in the opposite direction in the next compartment of the heating chamber. These cold cars being cooler, chill the air and it passes through the bottom openings 7 in the partition wall and passes up through the heated cars on the opposite track, and being heated thereby, ascends and escapes through the openings 7, thereby creating a circulation. There will also be a circulation of heat through the hollow tiles 17, as they communicate top and bottom with the heating chambers, and this will further greatly increase the heating efficiency of the furnace, and instead of there being a direct radiation of the heat from the flues 10, the hollow tiles provide for the passage of heated air which protects the furnace walls and at the same time gives better circulation.

It is apparent that instead of the use of the individual tiles forming the inner wall of the flue 10, other constructions may be employed providing for such a hollow wall,

and such modified constructions are included within the scope of my invention.

What I claim is:

1. In a heat treating furnace having a heating chamber, heating flues formed in the side walls of said furnace, a longitudinal partition wall dividing said chamber into two compartments, said partition having openings at its upper and lower portions, the inner sides of said walls of said heating flues forming side walls of said heating chamber having an air space communicating top and bottom with said heating chamber. 45

2. In a heat treating furnace having a heating chamber, heating flues formed in said walls of said furnace, a longitudinal partition wall dividing said chamber into two compartments, said partition having openings at its upper and lower portion, hollow tiles forming the inner wall of said heating flues and the side walls of said heating chamber, said hollow tiles communicating top and bottom with said heating chamber. 50

3. In a heat treating furnace having a heating chamber, heating flues formed in said walls of said furnace, a longitudinal partition wall dividing said chamber into two compartments, said partition having openings at its upper and lower portion, hollow tiles forming the inner wall of said heating flues to the side walls of said heating chamber, said tiles having beveled upper ends and communicating top and bottom with said heating chamber. 55

In testimony whereof, I the said CHARLES J. KIRK, have hereunto set my hand.

CHARLES J. KIRK.

Witnesses:

ROBT. D. TOTTEN,
A. E. CLANCY.
